Primary Examiner — Patricia A Palasik

(57) **CLAIM**

The ornamental design for a robot, as shown and described.

DESCRIPTION

FIG. 1 is a first perspective view of a robot showing the claimed design in accordance with the present disclosure; FIG. 2 is a second perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a perspective view of the robot, wherein a neck of the robot is in an extended position.

The broken lines in the Figures are for the purpose of illustrating portions of the article that form no part of the claimed design.

1 Claim, 9 Drawing Sheets
